UNITED STATES PATENT OFFICE.

HOWARD G. BARTLING, OF CHICAGO, ILLINOIS, ASSIGNOR TO SEWALL PAINT & VARNISH COMPANY, OF KANSAS CITY, MISSOURI, A CORPORATION OF MISSOURI.

RUBBING MACHINE.

Application filed March 27, 1925. Serial No. 18,807.

This invention relates to improvements in rubbing machines, particularly adapted though not necessarily limited in its use for rubbing varnished and polished surfaces, and one of the objects of the invention is to provide an improved machine of this character in which is embodied a rotatable rubbing element adapted to effectively rub curved, irregular, and uneven surfaces, the rubbing element being rotatable and provided with a spiral shaped work engaging faces or surfaces, adapting the same for contact with surfaces which are ordinarily difficult to reach.

15 A further object is to provide an improved portable power driven hand device of this character which will be comparatively light to handle and in which there is embodied a plurality of spirally arranged 20 rotatable rubbing faces operating in opposition to each other.

25 A further object is to provide an improved machine of this character which will be of a simple, durable and compact construction, and effective and efficient in operation.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

35 Figure 1 is a view partly in elevation and partly in longitudinal section of a machine of this character constructed in accordance with the principles of this invention.

Figure 2 is a vertical, sectional view taken 40 on line 2-2, Figure 1.

Figure 3 is a vertical, sectional view taken on line 3-3, Figure 1.

Figure 4 is an elevation of one of the rotatable members for supporting the rubbing elements, and with the rubbing strips in position.

Figure 5 is a detail view of the member for supporting the rubbing elements.

Figure 6 is a view of one of the filler mem- 50 bers.

Figure 7 is a diagrammatic bottom plan view of the rubbing elements.

In the present exemplification of this invention the numeral 10 designates a sup- 55 porting structure which may be of any de-

sired size and configuration and may be provided with a handle 11, by means of which the device may be manipulated. A portion 12 of the structure constitutes a shield which is adapted to extend over the rotatable rubbing elements.

In the present exemplification of this invention two rubbing rollers are shown, but it is to be understood that any number of these rollers may be provided according to 65 the size of the device which it is desired to produce.

Each of the rubbing rollers are preferably of sectional construction, that is to say each of these rollers preferably embody two sections 13, each section comprising a body portion, which is preferably cylindrical and of any desired diameter and length. Around the periphery of each of the sections is provided a series of spirally arranged grooves 75 14 of any suitable depth and these grooves run throughout substantially the length of the respective sections.

The rubbing elements 15 are constructed of a flexible textile fabric and is formed in 80 strips. These strips are comparatively wide with relation to their thickness and are secured to the respective sections of the rollers by one edge by placing one edge of the elements 15 in the grooves 14. The width of 85 the material from which the element 15 is formed is preferably somewhat less than the width of the grooves 14, so that after the elements 15 have been placed in position, 90 filler members 16 may be placed in the respective grooves so as to engage one face of the adjacent portions of the element 15 and co-operating with the adjacent wall of the groove to clamp the elements 15 in position. These filler members 16 are preferably 95 of a length slightly greater than the length of the grooves 14 in which they are seated so that one end of the element 15 will project slightly beyond the end 17 of the member 15, as shown more clearly in Figure 4. 100 The other ends of the filler members 16 preferably engage a collar or shoulder 18 on the section 13. When the elements 15 and filler members 16 are placed in position, a

105 collar 19 which encompasses the end of the roller, is adapted to engage the adjacent ends of the filler members 16 and the collar co-operates with the collar or shoulder 18 to clamp and hold the filler members 16 against 110 displacement.

- The outermost section 13 is preferably provided with screw threads 20 on its extremity to receive another collar 21 for holding the parts in position.
- 5 The outer extremity of each of the rollers is free and the threaded extremity 20 of each roller preferably projects for a considerable distance beyond the collar 21 so that additional rubbing elements 22 may be secured 10 to the end of the roller by means of another collar or nut 23, so that the end of the roller may be utilized for rubbing. The rubbing elements 22 may be of any desired configuration and are secured by one edge to the roller, the free edge of the elements 22 being preferably deflected over the collar 23 and the end of the roller section in any suitable manner, such as by means of a member 24, preferably in the form of a washer.
- 15 20 The outer edges of the strips 15 are free so that when the rollers are rotated, the free edges of the elements 15 will be deflected so that their side surfaces will be presented to the work and will cause a wiping action of 25 the strips upon the surface when pressure is exerted upon the implement through the medium of the handle 11.
- The rollers thus formed embodying the sections 13 and strips 15 with the associated parts are arranged end to end are secured 30 to a shaft 25 for rotation therewith in any desired or suitable manner, preferably by being keyed thereto as at 26. The end of the shaft 25 is preferably threaded as at 35 and passes through a wall or rib 28 in one of the sections 13. A nut 29 is threaded on the end of the shaft 25 and engages the wall or rib 28 and holds the sections 13 against displacement. A collar or shoulder 30 is 40 provided on the shaft 25 against which one end of one of the sections 13 abuts and cooperates with the nut or collar 29 for holding the parts against displacement.
- 45 The shaft 25 is rotatably supported in any suitable manner preferably by means of a ball bearing element 31 which is threaded into a recess 32 in the supporting body 10 of the implement. A thrust bearing 33 may be provided for receiving and supporting 50 the end of the shaft. Within the chamber or recess 32 is arranged a gear 34, which is secured to the shaft 25 for rotation therewith.
- 55 Two rollers thus formed may be provided in each machine and are arranged so that they will be parallel to each other and are adapted to be rotated in opposite directions by means of a gear 35 which meshes with the gears 34. The gear 35 receives its motion 60 from any suitable source of driving power (not shown) and which power is communicated to the gear 35 through the medium of a shaft 36. This shaft 36 preferably passes through a portion of the handle so as to be 65 out of the way of the operator.

The rubbing strips 15 which are arranged about the roller sections 13 and which are secured to each of the shafts 25 are so arranged that they will run in opposition to each other that is so that during the operation of the device the tendency of the flexible rubbing strips 15 is to feed the rubbing material toward the longitudinal centers of the shafts 25, thereby preventing the material from being thrown outwardly and away 75 from the work by the operation of the rubbing elements.

The shield 12 also prevents the material from being thrown out by the rubbing elements.

80 With this improved construction it will be manifest that the device is of a simple construction and can be easily manipulated and will be adapted for use on even or uneven and irregular surfaces. Furthermore, the rubbing elements being flexible and being arranged as shown, will render it possible to reach corners and all portions of curved surfaces.

85 While the preferred form of the invention 90 has been herein shown and described it is to be understood that various changes may be made in the details of construction and in the combination and arrangement of the several parts, within the scope of the claims, 95 without departing from the spirit of this invention.

95 What is claimed as new is:—

100 1. A portable hand holding rubbing machine including a roller, rubbing strips of flexible textile fabric comparatively wide with relation to their thickness, secured by one edge to the roller, said strips extending in general directions lengthwise of and about the roller, whereby said strips are adapted to present their side surfaces for a wiping action against the work, and means for driving the roller.

110 2. A portable hand holding rubbing machine including a roller, rubbing strips of flexible textile fabric comparatively wide with relation to their thickness, secured by one edge to the roller, said strips extending in general directions lengthwise of and about the roller, whereby said strips are adapted to present their side surfaces for wiping against the work, means for driving the roller, one extremity of the roller being free, and a rubbing element of flexible textile fabric carried by said free end of the roller.

115 3. A rubbing machine including a roller, separate strips of flexible textile fabric comparatively wide with relation to their thickness secured along one edge of the said roller to extend in directions lengthwise of the axis thereof and spirally thereabout, whereby the strips are adapted to present their side surfaces for a wiping action against the work, the outer edges of the strips being 120 125 130

- free, and means for removably securing the strips to the said roller, the said strips being arranged in opposed spirals about said roller and arranged end to end.
5. A rubbing element including a roller having a groove in the periphery thereof, said groove extending spirally thereabout, an extended flexible strip, one edge of said strip being seated in the groove, the outer edge 10 of the strip being free, a filler member seated in said groove and engaging the strip, and a fastening device adjustably connected with one end of said roller for removably securing said strip and filler member against 15 displacement with respect to the roller.
6. A rubbing machine including a pair of rollers arranged side by side, separate continuous strips of flexible material secured along one edge to each of said rollers to 20 extend in directions lengthwise of the axis thereof, the outer edges of the strips being free, the strips on each of the rollers being arranged in separate groups and extending spirally in opposite directions about said 25 rollers whereby the operative effect of one group of strips is substantially opposite to that of the other group, and means for rotating the said rollers.
7. A rubbing machine including a roller, said roller including separate groups of oppositely arranged rubbing strips of flexible textile material extending in general directions lengthwise of the roller and comparatively wide with relation to their thickness, 30 said strips operating to present their side surfaces for a wiping action against the work, whereby said strips feed a rubbing compound in directions away from the ends of the roller and towards the longitudinal center of the roller.
8. A rubbing machine including a pair of rollers arranged side by side, each of the said rollers including flexible rubbing elements secured along one edge to the respective rollers and extending about the rollers, 35 the elements on said rollers extending in opposite directions to each other, additional flexible rubbing elements secured to one end of each of the respective rollers to project beyond said end, the outer extremities of 40 the last recited elements being free, and means for rotating the said rollers.
9. A portable hand holding rubbing machine including two elongated rollers, each of the rollers being of a length considerably 45 greater than the diameter thereof, rubbing strips of textile fabric connected by one edge with each of the rollers, the said strips being comparatively wide with relation to their thickness whereby the strips are adapted to present their side surfaces for a wiping action against the work and whereby the said wiping surfaces will be substantially coextensive with the length of the roller, and means for rotating the rollers in opposite 50 directions with respect to each other.
10. A portable hand holding rubbing machine including two elongated rollers, each of the rollers being of a length considerably 55 greater than the diameter thereof, rubbing strips of textile fabric connected by one edge with each of the rollers, the said strips being comparatively wide with relation to their thickness whereby the strips are adapted to present their side surfaces for a wiping action against the work and whereby the said wiping surfaces will be substantially coextensive with the length of the roller, the said strips on one of the rollers being 60 inclined to the longitudinal axis of the roller, and means for rotating the rollers in opposite directions with respect to each other.

In testimony whereof I have signed my name to this specification, on this 16th day of March, A. D. 1925.

HOWARD G. BARTLING.
